UNITED STATES PATENT OFFICE

132,244

DESIGN FOR A BABY'S OBSERVATION STIMULATING DEVICE

Abby Beveridge Baum, Seattle, Wash.

Application September 15, 1941, Serial No. 103,355

Term of patent 7 years

To all whom it may concern:

Be it known that I, Abby Beveridge Baum, a citizen of the United States, residing at Seattle, in the county of King, State of Washington, have invented a new, original, and ornamental Design for a Baby's Observation Stimulating Device, of which the following is a specification, reference being had to the accompanying drawing, forming part thereof, wherein

Fig. 1 is a perspective view of a baby's observation stimulating device, showing my new design; and

Fig. 2 is a side elevational view thereof.

The characteristic feature of the design comprises the heart-shaped cushion-like element having distinctively different button-like elements flexibly attached to and spaced from the surface thereof so as to be easily grasped by a baby, substantially as shown.

I claim:

The ornamental design for a baby's observation stimulating device, substantially as shown and described.

ABBY BEVERIDGE BAUM.
